US00D996750S

(12) **United States Design Patent** (10) **Patent No.:** **US D996,750 S**
(45) **Date of Patent:** **** Aug. 22, 2023**

(54) **VACUUM CLEANER**

(71) Applicant: **SHARKNINJA OPERATING LLC**,
Needham, MA (US)

(72) Inventor: **Scott B. Niedzwecki**, Walpole, MA
(US)

(73) Assignee: **SHARKNINJA OPERATING LLC**,
Needham, MA (US)

(**) Term: **15 Years**

(21) Appl. No.: **29/722,721**

(22) Filed: **Jan. 31, 2020**

(51) **LOC (14) Cl.** **15-05**

(52) **U.S. Cl.** **D32/22**
USPC **D32/22**

CLAIM

The ornamental design for a vacuum cleaner, as shown and described.

DESCRIPTION

FIG. 1 is a perspective front view of a first embodiment of a vacuum cleaner showing the claimed design;
FIG. 2 is front view of the vacuum cleaner of FIG. 1;
FIG. 3 is rear view the vacuum cleaner of FIG.1;
FIG. 4 is right side view of the vacuum cleaner of FIG. 1;
FIG. 5 is left side view of the vacuum cleaner of FIG. 1;
FIG. 6 is top view of the vacuum cleaner of FIG. 1; and
FIG. 7 is bottom view of the vacuum cleaner of FIG. 1;
FIG. 8 is a perspective front view of a second embodiment of the vacuum cleaner showing the claimed design;
FIG. 9 is front view of the vacuum cleaner of FIG. 8;
FIG. 10 is rear view the vacuum cleaner of FIG. 8;
FIG. 11 is right side view of the vacuum cleaner of FIG. 8;
FIG. 12 is left side view of the vacuum cleaner of FIG. 8;
FIG. 13 is top view of the vacuum cleaner of FIG. 8; and,
FIG. 14 is bottom view of the vacuum cleaner of FIG. 8.
The broken lines in the drawings depict portions of the vacuum cleaner that form no part of the claimed design.

1 Claim, 12 Drawing Sheets
